UNITED STATES PATENT OFFICE.

ALBERT A. MARTELL, OF WOONSOCKET, RHODE ISLAND, ASSIGNOR TO THE TAFT-
PEIRCE MANUFACTURING COMPANY, OF WOONSOCKET, RHODE ISLAND, A COR-
PORATION OF RHODE ISLAND.

ADJUSTABLE REAMER-HEAD.

1,376,450.

Specification of Letters Patent.

Patented May 3, 1921.

Application filed July 7, 1917. Serial No. 179,191.

To all whom it may concern:

Be it known that I, ALBERT A. MARTELL, a citizen of the United States, and a resident of the city of Woonsocket, in the county of Providence, State of Rhode Island, have invented certain new and useful Improvements in Adjustable Reamer-Heads, of which the following is a specification.

This invention relates broadly to small tools and more particularly to a reamer.

The principal object of the present invention is to provide a reamer wherein the cutting blades are removable and are mounted spirally relative to the axis of the reamer in such manner that a continuation of the spirals of certain blades would intersect the continuation of spirals of other blades, and with diametrically opposite blades inclined in the same direction.

20 A still further and primary object of the present invention is to provide a reamer with movable blades adapted to be controlled by a micrometer mechanism to permit the accurate adjusting of the blades to cut on predetermined diameters.

25 A still further object of the present invention is the provision in a reamer of angularly disposed cutting blades relatively to the axis of the reamer with the angles of certain blades complementary to the angles of other blades in such manner as to counteract any effect which might be produced by providing all of said blades with the same inclination to the axis of the reamer.

30 Other and further objects of the present invention will in part be obvious and will in part be pointed out hereinafter by reference to the accompanying drawings wherein like parts are represented by like characters throughout the several figures of the drawings.

40 Figure 1 is a view illustrating a reamer in accordance with my invention with the parts assembled, showing a portion in section to more clearly illustrate the construction.

45 Fig. 2 is a view illustrating the body of the reamer.

50 Fig. 3 is an end view of one of the micrometer rings.

Fig. 4 is an end view of the body portion.

Fig. 5 illustrates the reamer in accordance with my invention wherein the advancing portion of the reamer is provided with

a guiding collar, and showing a portion of the reamer in section to more fully illustrate the construction.

Fig. 6 is a view illustrating the body of the reamer shown in Fig. 4.

The reamers forming the subject matter of the present invention, while useful for general purposes, are more particularly adapted for accurately reaming bearings, and especially bearings of automobile engines and the like of predetermined dimensions. Heretofore in the art of reamers of this character having adjustable or removable blades, it has been customary to mount the blades straight in the reamer body and since each blade is removable and is supported on only a portion of the base there is possibility of vibration being set up within the blade and the result is not entirely satisfactory. A vibrating blade necessarily produces a more or less roughened cut. Where blades are angularly disposed the cutting action is more of a shear and it is not at right angles to the face of the blade so that the tendency of vibrating the blade is minimized. However, where each blade is set with the same inclination any action of a preceding blade which produces a microscopic variation or wave on the reamed surface strikes the full face of a succeeding blade and may, under certain circumstances, cause the succeeding blade to emphasize or amplify the fault produced by the preceding blade.

In the preferred form the present invention overcomes the difficulties previously specified by inclining certain of the removable cutting blades on one spiral relatively to the axis of the reamer, and inclining certain other cutting blades at a different spiral, preferably inclining opposite blades in the same direction to produce a diametrically opposed uniform support for the blades. Since certain blades are at a different inclination from other blades it will be noted that any fault produced by an individual blade striking a hard spot or hard particle in the metal being reamed will be counteracted by the succeeding blade of different angularity which will ream out by a shearing action any fault produced by a preceding blade. In reaming the bearings for automobile engines it is desirable that the individual bearing be reamed to fit the in-

2
 5 individual crank shaft bearing which the engine bed bearing receives and supports. Crank shafts are not usually uniform in diameter as to all of the various bearing points. In view of this fact to produce accurate fits it is necessary that each engine bed journal or bearing be reamed on a specific diameter which agrees with the portion of the crank it is to carry. Ordinarily this 10 operation requires caliper of the crank shaft at its bearing points and also the caliper of the reamer head. The latter operation is the more difficult of the two since it is necessary to caliper across cutting faces. 15 The caliper of the reamer in the present invention is automatically provided for by equipping the blades with suitable adjusting angles seated upon supporting wedges and providing the blade holders with micrometer mechanism whereby the diameter of the working faces of the reamer may be determined by setting the micrometer devices. 20 The present invention also includes a guiding collar which under certain uses of the reamer may be used to center the reamer head in the opening that is being reamed. 25 Referring now more particularly to the drawings and especially to Figs. 1 and 2, the 30 body portion 1 of the reamer is provided with a blade supporting hub 2 in the central part of the body portion with a threaded advancing end 4 and a threaded micrometer end 5 adjacent which is a non-threaded portion 6. Spirally arranged grooves are provided in the body portion and certain of the grooves, as 7, are spirally inclined in one direction relatively to the axis A of the reamer, whereas other of the grooves, as 8, are inclined in the opposite direction. Preferably the grooves on one side of the reamer are inclined on the same spiral as the grooves diametrically opposite. Blade supports 9 comprising small wedge shaped members 45 provided with short cylindrical studs are adapted to fit in the grooves 7 and 8 with the bases of the wedges seated on the bases of the grooves and the short studs fitting within the holes 10 provided in the body portion. The inclinations 11 on the wedges of the blade supports 9 are very accurately formed to be parallel when the supports are in position in the grooves and constitute mounts which carry the cutting blades 12 by 50 coöperating with the accurately formed parallel surfaces 14 and 15 formed on the under surfaces of the blades. Each end of the cutting blades 13 is beveled, as at 16 and 17, and the bevel 16 coöperates with a screw 55 threaded collar 18 which is adapted to be mounted on the front end of the body portion and to rotate on the threads thereon, whereas the bevel 17 coöperates with one of the micrometer collars 19 which is provided 60 on its inner surface with guiding grooves 20

that accurately fit over and coöperate with studs 21 mounted in the non-threaded portion 6 of the body portion. This construction permits the micrometer collar 19 to slide endwise relatively to the body portion 70 but prevents any rotative movement of this collar on the body portion. The other micrometer member 22 is screw threaded on its inner surface to coöperate with the screw threaded portion 5 on the body portion. The 75 micrometer member 19 carries a zero and a fractional scale 24, while the other micrometer collar 22 carries a full micrometer scale 25. By the coöperation of these two scales the micrometer may be read to small dimensions, for example, one-ten thousandth of an inch, that is when the collar 18 is slightly loosened and the micrometer collar 22 advanced one division of the scale 24 each blade 12 will move forward on the wedge 80 blade supports 9 a distance sufficient to increase a radial line to the cutting edge one-half of the one-ten thousandth of an inch, since the radius is increased this much the diameter obviously will be increased one-ten thousandth. In order to facilitate the movement of the collars 18 and 22, these collars are preferably provided with openings 26 which are adapted to coöperate with a spanner wrench to loosen or tighten these members as may be desired. Preferably the body portion of the reamer is provided with stub screws 27 whereby the reamer may be fixedly mounted upon a suitable reamer shaft. In order to enable the reamer to be accurately seated the stub screws may be mounted upon diametrically opposite sides of the reamer body, as is shown in Fig. 4.

Referring now more particularly to Figs. 5 and 6, the construction of the reamer is 105 substantially the same as that illustrated in the preceding figures with the exception that the body portion is slightly extended thereby providing a non-threaded portion 28 on the advancing end, which portion carries a 110 guiding collar 29 that is grooved to coöperate with studs 30 so that this collar, as well as the micrometer collar 19, has sliding but no rotative movement relatively to the body portion. This type of reamer carrying the 115 guiding collar is adapted more particularly for reaming and finishing individual bearings without particular reference to alining the bearing being operated upon with any other bearing or point of departure.

120 It will be noted that the micrometer collar 19 is provided with a plurality of grooves 20 which are adapted to coöperate with the stud 21 on the body portion. The plurality of the grooves 20 permits adjustment of the 125 zero and fractional scale 24 through ninety degree angles relative to the body portion. This ninety degree angular adjustment of the zero scale 24 permits grinding of the blades when dulled, and re-adjustment of 130

- the zero scales to permit a zero reading relative to the full micrometer scale 25 on the micrometer collar 22. Thus it will be seen that if originally the parts were so adjusted 5 that when the zero lines on the scale 24 and on the scale 25 were exactly opposite the reamer blades would caliper exactly two inches, the blades could be slightly reground, the collar 19 advanced ninety degrees thereby 10 sliding the blades forward and outward on the inclinations 11 on the blade supports 9 and the blades then accurately ground so that the zeros would again, when opposite, indicate the reamer would caliper at exactly 15 two inches. In other words the plurality of slots in the micrometer collar 19 enables the maintenance of the accurate and true reading of the scales without necessitating undue grinding away of the cutting blades.
- 20 Realizing that it is possible to vary the physical embodiments of my invention within the scope of the appended claims, I desire that it be understood that the specific disclosure herewith is illustrative and not intended to be considered in the limiting sense.
- Having thus described my invention what I claim is:—
1. In a reamer of the character described, in combination, a plurality of radially adjustable cutting blades, suitable supports for said cutting blades, means for radially adjusting said cutting blades, said means comprising micrometer devices including a circumferentially adjustable non-rotatable ring adapted to abut against said blades, means to permit rotative adjustment of said ring and a rotatable ring coöperating with said adjustable ring, said rotatable ring being adapted to produce a longitudinal movement of said non-rotatable ring.
  2. A reamer of the character described, comprising in combination, a plurality of angularly disposed diametrically opposed blades, certain of said blades being set at angles different from other of said blades, means to support said blades, devices for adjusting said blades radially to predetermined dimensions, said means comprising a circumferentially adjustable non-rotatable collar mounted to abut against the ends of said blades, a rotatable screw threaded collar coöperating with said non-rotatable collar, and micrometer scales on said collars, substantially as specified.
  3. As an article of manufacture, a reamer comprising a body portion, a plurality of diametrically opposed blades arranged in pairs and angularly disposed on said body portion, with the angle of one pair of blades being different from the angle of another pair of blades and with the diametrically disposed blades of each pair being inclined in the same direction and set at equal angles
- whereby the cutting edge of one blade is diametrically opposite throughout its length 65 to the cutting edge of another blade of the same pair.
4. In a reamer of the character described, in combination, a body portion, a plurality of radially adjustable blades mounted on said body portion, means to adjust said blades radially, said means including a member provided with a zero line comprising a line of departure and a micrometer member carrying a micrometer scale readable relatively to said line of departure, and means whereby said member provided with the line of departure is adjustable relatively to said body portion whereby said line of departure may be adjusted to agree 80 with a predetermined calibration after said blades have been resharpened.
5. In a reamer of the class described in combination a main body portion, blades mounted on said body portion, and means for adjusting said blades radially of the body portion, said means comprising a circumferentially adjustable non-rotating ring carrying a zero scale, and a rotatable member coöperating therewith and carrying a micrometer scale.
6. In a reamer of the class described, in combination a main body portion, blades mounted on said body portion, and means for adjusting said blades radially of the body portion, said means comprising a circumferentially adjustable slidably mounted non-rotating ring carrying a zero scale, and a rotatable member coöperating therewith and carrying a micrometer scale.
7. In a reamer having removable blades adaptable for sharpening, the combination of means for compensating for the metal removed by sharpening, said means comprising a ring having a zero scale and adjustable to different circumferential positions relative to the reamer, and means for moving said ring longitudinally of the reamer when in the said adjusted positions.
8. In a reamer, the combination of a body portion, a plurality of blades adjustably mounted upon said body portion, said blades having inclined end portions, a ring screw-threaded on the forward end of said reamer and comprising a guiding member for inserting said reamer in an opening to be reamed, a sliding ring adjacent the other end of the reamer, said screw-threaded ring and said sliding ring being under-cut to cooperate with the inclined end portions of the blades to retain the blades in position on the reamer body, and a second screw-threaded ring comprising a clamp ring adapted to clamp said sliding ring against the rear end of the blades.

ALBERT A. MARTELL.
